(57) **CLAIM**

The ornamental design for a skimmer protector, as shown and described.

DESCRIPTION

FIG. 1 is a perspective view of a skimmer protector showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a perspective view of the skimmer protector in use. The broken line illustration shows environmental structure and forms no part of the claimed invention. Undisclosed and partially disclosed surfaces are plain and unornamented.
